UNITED STATES PATENT OFFICE

98,210

DESIGN FOR A BUILDING

George Edwin Brumbaugh, Gwynedd Valley, Pa.,
assignor to The Galleys, Inc., Beltsville, Md., a
corporation of Maryland

Application August 28, 1935, Serial No. 58,341

Term of patent 14 years

To all whom it may concern:

Be it known that I, George Edwin Brumbaugh, a citizen of the United States, residing in Gwynedd Valley, in the county of Montgomery and State of Pennsylvania, have invented a new, original, and ornamental Design for a Building, of which the following is a specification, reference being had to the accompanying drawings, forming part thereof, wherein:

Fig. 1 is a perspective view of a building made in accordance with this design;

Fig. 2 is a front elevational view of the building shown in Fig. 1, with the front stay wires for the aerial posts omitted;

Fig. 3 is an end elevational view of the building shown in Fig. 1, with the end stay wire for the aerial post omitted; and

Fig. 4 is a plan view of the building shown in Fig. 1, with the aerial wire and the stay wires for the aerial posts omitted.

I claim:

The ornamental design for a building, substantially as shown and described.

In testimony whereof, I have hereunto signed my name this 26th day of August, A. D., 1935.

GEORGE EDWIN BRUMBAUGH.
